W. B. PUMPHREY

FILTERING DEVICE

Filed Jan. 11, 1926

FIG. 1

FIG. 2.

INVENTOR.
WILLIAM B. PUMPHREY.
BY
Harry P. Schroeder
ATTORNEYS.

UNITED STATES PATENT OFFICE.

WILLIAM B. PUMPHREY, OF SEQUOIA, CALIFORNIA.

FILTERING DEVICE.

Application filed January 11, 1926. Serial No. 80,452.

The present invention relates to improvements in filtering devices, and its particular object is to provide a filter for home use that may be secured in the water system and 5 allows a small stream of water to continuously seep through a filtering material. One particular advantage of my device is that it is self-cleaning so far as a fan is disposed in close relation to the inner faces 10 of the filtering walls and is actuated every time water is withdrawn from the system so as to clean the walls. The device is furthermore self-cleaning in so far as normally the pressure of the water causes a small 15 amount to be forced through the filtering material which would tend to leave small deposits of material on the inner faces of the filtering material; but when the water is turned on for the purpose of withdrawing 20 water from the system the pressure upon the walls of the filtering material ceases and is then changed to suction so that a cleaning action takes place every time the water is turned on, not only due to the scraping action 25 of the fan, but also due to the suction caused thereby.

It is further proposed to provide means for heating the water about the filtering walls so that the water becomes sterilized. 30 Further objects and advantages of my device will appear as the specification proceeds.

The preferred form of my invention is illustrated in the accompanying drawing in 35 which:

Figure 1 shows a vertical axial section through my device, and

Figure 2 a central transverse section on a reduced scale.

40 While I have shown only the preferred form of the invention, it should be understood that various changes or modifications may be made within the scope of the claims hereto attached without departing from the 45 spirit of the invention.

A ring 1 supported on a base 2 forms an annular chamber 3 and has two sections 4 and 6 of a casing engaging opposite ends of the ring with a central shaft 7 extending 50 through both ring and casing sections, and allowing the latter to be tightened upon the ring by means of nuts 8. The casing sections 4 and 6 are filled with the walls of filtering material 9, and are recessed in their 55 outer ends, as shown at 11, to allow water

to filter from the central space within the ring through the filtering walls into the recesses 11, which communicate through radial passages 12 with annular recesses 13, surrounding the shaft 7 and communicating 60 through radial ports 14 with a central bore 16 in the shaft, which leads to the spout 17 from which filtered water is discharged.

The base 2 of the ring is provided with 65 threaded ports 18 and 19 adapted for connection to a water pipe, the water entering from the port 18 and a passage 21 into the chamber 3 and leaving through a passage 22 and the port 19. A fan 23 is supported on the shaft 7 between the two walls of 70 filtering material and is imparted revolving motion by the running water whenever a faucet is opened for the purpose of withdrawing water from the system.

75 Washers 24 are preferably used on opposite sides of the fan where the same joins the central shaft so as to prevent the water from leaking around the outside of the shaft.

Suitable electric heating elements 26 may 80 be accommodated in a groove 27 in the ring and allow the water to be heated for the purpose of sterilizing the same and the walls of filtering material.

The manner in which my device works 85 should be readily understood from the foregoing description; the ports 18 and 19 are connected into the water pipe at any suitable place. Water is thereby allowed to enter the chamber 3 and will slowly seep through the 90 filtering material on opposite sides of the chamber into recesses 11 and from there through the ports 12 into the annular recesses 13 and further through the ports 14 into the bore 16 in the shaft 7 so as to be 95 discharged through the spout 17. When any faucet is opened in the water system to withdraw water for other purposes the water runs through the chamber 3 and imparts rotary motion to the fan 23, the blades of which

100 being in close proximity to the walls 9 of filtering material clean the same of any scum or the like that may have collected on the faces thereof. It should also be noted that, while ordinarily the water is forced 105 through the filtering material, the pressure ceases when a faucet is opened and changes to suction so that, if any scum is collected on the inner faces of the filtering material, or has slightly penetrated the same, it will 110

be drawn out and carried with the water, which, of course, is used for other than drinking purposes.

The heating elements may be used to sterilize the water, and to clean the filtering material by passing the heated water therethrough.

I claim:

1. A filtering device comprising a ring, a centrally disposed shaft, two casing sections adapted for engagement with opposite sides of the ring, means for tightening the sections upon the ring, filtering walls within the two sections leaving the space within the ring clear, and means for connecting the said space with a water pipe, the sections being formed with recesses in opposite walls

thereof adapted to receive water seeping through the filtering material, and the recesses communicating with a bore in the shaft for guiding the water outwardly.

2. A filtering device of the character described, comprising an enclosure adapted to be fitted into a water distributing system so as to allow water to run therethrough, the enclosure having walls of filtering material allowing a small amount of the water to continuously seep through the same, electric heating elements for heating the water, and scraping means operated by water running through the enclosure for cleaning the inner faces of the walls.

In testimony whereof I affix my signature.

WILLIAM B. PUMPHREY.
